CLAIM

The ornamental design for a panel for a public video terminal enclosure, substantially as shown and described.

DESCRIPTION

FIG. 1 is a front view in perspective of a panel for a public video terminal enclosure showing our new design;

FIG. 2 is a top plan view thereof;

FIG. 3 is a front elevation thereof;

FIG. 4 is a bottom plan view thereof; and

FIG. 5 is a side elevation thereof, with the view of the side opposite being essentially a mirror image of the side shown.

FIG. 1

FIG. 2

FIG. 3

FIG. 4

FIG. 5
